UNITED STATES PATENT OFFICE.

FRANK A. RYTHER, OF CHICAGO, ILLINOIS.

CORD TYING AND FASTENING DEVICE.

1,257,027.

Specification of Letters Patent. Patented Feb. 19, 1918.

Application filed February 26, 1917. Serial No. 151,081.

To all whom it may concern:

Be it known that I, FRANK A. RYTHER, a citizen of the United States, residing at Chicago, in the county of Cook and State 5 of Illinois, have invented certain new and useful Improvements in Cord Tying and Fastening Devices; and I do declare the following to be a full, clear, and exact description of the invention, such as will enable others skilled in the art to which it 10 pertains to make and use the same.

This invention relates to cord tying and fastening devices and more especially to that 15 class of tying devices which are applied to packages of letters, cards and the like for securing or fastening the same.

The invention has for its object the provision of a tie of this character which can be used indefinitely without any deterioration 20 of parts.

Another object is to provide a device of this character which is easily manufactured, simple of construction, and easily operated.

To this end my invention consists of the 25 device illustrated in the accompanying drawings and described and claimed in the following specification in which like reference characters designate corresponding parts.

30 In the drawings:—

Figure 1 is a plan view of my device;

Fig. 2 is a side elevation of Fig. 1;

Fig. 3 is a perspective view;

Fig. 4 is a view in perspective showing 35 my invention as applied in one stage of the operation of tying;

Fig. 5 is a like view in perspective at another stage of the tying of the cord;

Fig. 6 is a view showing my device applied to a package or the like when in secured position;

Fig. 7 is an illustration of the convolutions of the cord when in secured position on my fastener; and

Fig. 8 is a sectional view taken on the line 8—8 of Fig. 1.

Referring to the drawings, my invention consists of a piece of wire bent in the form of the well known wishbone designated by 50 the numeral 1. It consists of a body portion 2 having an eye 16 formed at one end and slanting upwardly from the plane of the body portion 2. At the opposite end of this body portion a lug 3 is formed which 55 projects laterally and is curved slightly backward upon the body portion 2. At the

end 4 of the lug 3 the wire is bent upon itself and continued in the opposite lateral direction which is arcuately curved in plan view backward upon the body 2, to form 60 an arm 6. The portions of the wire comprising the lug 3 are preferable integrally connected by any suitable means which, in the present embodiment, comprises a section of solder inserted between the two portions of the wire designated as 7. From its point of commencement to its terminal 8 the arm 6 is reversely curved in end view to provide a raised portion 9 at the end of the body 2 adjacent the lug 3 in order 70 to accommodate thereunder a knot 10 of the rope or cord 11 which is secured thereto. The lug 3 is formed substantially within the line of curvature of the arm 6 so that the body 2 when resting upon the surface of 75 the package or bundle 12 to be tied is slanted upward toward the meeting end of the body and the lug as shown at 13. Adjacent the terminal of the arm 6, said arm is bent upwardly from the low point of the reverse 80 curve to form a guide member 14. This guide member is extended upwardly in a plane occupied by the upwardly extending eye 16. The arm 6 is bent rearwardly upon the body 2 to a point substantially in line 85 with but spaced laterally from the eye carrying end of the body 2. This construction of the arm 6 and the body 2 provides a substantially V-shaped slot 15 in which the cord or rope 11 is engaged. 90

In the operation of this device, one terminal of the cord or rope with which the package is to be bound is knotted firmly in the eye 16 which, owing to its upward slant, allows play for the cord so that it will 95 not be impressed into the package to be bound. The cord is then continued over one end of the package around the same and up over the opposite end. The cord is then carried under the raised guide portion 14 of the arm 6 and given a pull in the direction of the lug 3 which carries it under the arm 6 and beneath the raised portion 9 of the arm. It is then carried over the body 2 and continued beneath the lug 3 100 and given a pull in the reverse lower direction which brings the cord again to the raised portion 14 of the arm 6 as illustrated in Fig. 4. It is then inserted again under the raised portion of this arm and 105 given a pull in the direction of the lug 3, and lastly given a downward pull in a par-

allel direction with the line of the cord already secured on the package as illustrated in Fig. 5. This will form a secure knot which has its bulged portion directly under the raised portion 9 of the arm 6 and end of the raised portion 13 of the body 2 and is securely held in the slot 15.

To unfasten this tie, it is merely necessary to reverse the operation. If further 10 tightening is desired, a pull upon the free end of the cord will secure the necessary adjustment.

Having thus fully described my invention, what I desire to secure by Letters-Patent 15 is:—

1. A fastening device of the class described comprising a section of wire to form a body, said wire being bent laterally and upon itself in the opposite direction at one 20 end of said body to form an arm in angular relation with said body, said bent portions being connected together forming a lug on the opposite side of the body, and cord retaining means at the other end of said body.

2. A fastening device of the class described comprising a section of wire to form a body bent laterally at one end thereof to form a lug projecting from said end and bent laterally again upon itself in the opposite 30 direction to form an arm on the opposite side of said body, said arm being curved

backward upon said body in angular relation with said arm and body, the said bent portions of the wire comprising the said lug being integrally connected throughout the 35 length of the lug, and suitable cord retaining means at the other end of said body.

3. A fastening device of the class described comprising a body, a lug projecting laterally from one side of the body, an arm 40 projecting from said lug and in the opposite direction and in angular relation to said body to form a slot for engagement with a cord therein, said arm being reversely curved.

4. A fastening device of the class described comprising a body, a lug projecting laterally from one side of the body, an arm 45 projecting from said lug and in the opposite direction and in angular relation to said body to form a slot for engagement with a cord therein, said arm being reversely curved, cord retaining means on the other end of said body.

In testimony whereof I have hereunto set 55 my hand in the presence of two subscribing witnesses.

FRANK A. RYTHE.
